INVENTOR.

Gilbert R. Denton

UNITED STATES PATENT OFFICE.

GILBERT H. DENTON, OF DENVER, COLORADO, ASSIGNOR TO JOHN ALBERT FERGUSON, OF DENVER, COLORADO.

PRESS FOR MOLDING BUILDING-BLOCKS.

SPECIFICATION forming part of Letters Patent No. 769,819, dated September 13, 1904.

Application filed December 15, 1903. Serial No. 185,272. (No model.)

To all whom it may concern:

Be it known that I, GILBERT H. DENTON, a citizen of the United States, residing at Denver, in the county of Denver and State of Colorado, have invented certain new and useful Improvements in Presses for Molding Building-Blocks; and I do declare the following to be a full, clear, and exact description of my invention, such as will enable others skilled in the art to which it appertains to make and use the same, reference being had to the accompanying drawing, forming a part of this specification, in which similar letters of reference indicate corresponding parts.

My invention relates to a class of presses adapted to be used for pressing building-blocks composed of cement or any composition material that will harden when seasoned.

The objects of my invention are to provide a press that will be efficient for the purposes for which it is adapted, one that is simple in its construction and operation, and one that can be readily adjusted.

I refer now to the drawing in further explaining the nature and objects of my invention, in which the figure is a central longitudinal cross-section of my invention.

In more fully referring to the drawing, A represents the base of the press, preferably 30 constructed of cast-iron. It is provided with four sets of lugs similar to those shown in the drawing. Those shown in the drawing are indicated by A' and A''. These lugs have apertures extending therethrough, as illus-

trated. The base A has four upright posts secured thereto, as will be made manifest by consulting the drawing. The posts shown in the drawing are represented by A³ and A⁴.

B designates the cast-iron platform, which is 40 provided with apertures in the four corners thereof through which the upright posts are adapted to pass, as illustrated. The platform B is slidably mounted on the posts A³ and A⁴ and is provided, on the bottom thereof, with lugs 45 similar to those shown on the drawing. (Designated by B' and B'' for the uses hereinafter specified.) A pair of vertically-disposed brackets (one of which is indicated by A⁵) are secured in a suitable manner to the base por-

tion A. These brackets have bearings or 50 journal-boxes through which passes the shaft or journal. (Indicated by A⁶.) Secured to this journal are two cranks, one of which is represented by A⁷. To these cranks are pivoted four bars or rods (two of which are designated 55 by A⁸ and A⁹) in the manner shown in the drawing. The opposite ends of these bars or rods are pivoted to suitable toggle-arms, as illustrated in the drawing and indicated by A¹⁰, A¹¹, A¹², and A¹³. These toggle-arms are 60 pivoted to the lugs on the base A and on the movable platform B. Two levers are keyed to the shaft A⁶ (one of which is indicated by A¹⁴) by means of which said shaft is revolved, causing the cranks to force the toggle-arms 65 into a horizontal position by means of the rods or bars connecting said cranks with said toggle-arms, which in turn raise the movable platform. (Represented by B.)

C represents an adjustable frame provided 70 with apertures in the corners thereof and adapted to be moved upward and downward by means of internally-threaded nuts, (two of which are designated by C' and C''), said nuts being rotatably mounted on the frame, as 75 shown, and adapted to engage the externally-threaded ends of the posts A³ and A⁴. These nuts are provided with sprocket-teeth, (indicated by C³ and C⁴), and over which the sprocket-chain (designated by C⁵) is adapted to 80 operate, thus facilitating the adjustment of all the nuts simultaneously, as will be made manifest by consulting the drawing.

It is obvious that the operation of my press is simple and as follows: The adjustable frame 85 C is first placed at such a height that the distance between that plate and the plate B is such as to make the finished block of the right thickness. The mold containing the material to be pressed is then placed upon the movable 90 platform. (Represented by B.) The lever is then thrown downward, which operation forces the movable platform B upward, thus effectually pressing the parts of the mold together and producing the desired result upon 95 the material contained in the mold.

Having thus described the nature and objects of my invention, together with the man-

ner of constructing and applying the same, what I claim as new, and desire to secure by Letters Patent of the United States, is—

1. In a press, the combination with a base, 5 of the threaded guide-rods secured thereto, a platform slidably mounted on the guide-rods, an adjustable frame carried by said rods and arranged above the movable platform, adjusting-nuts provided with peripheral teeth rotatably mounted on said frame and engaging the threaded ends of the guide-rods, a sprocket-chain 10 engaging the teeth on said adjusting-nuts, and means for reciprocating the platform, substantially as specified.
- 15 2. In a press, the combination with a base, of the supporting-brackets secured thereto, a shaft provided with crank-arms journaled in said brackets, vertically-disposed threaded guide-rods secured to the base, a platform

slidably mounted on the guide-rods, an adjustable frame carried by said rods and arranged above the platform, adjusting-nuts provided with peripheral teeth rotatably mounted on the frame and engaging the threaded ends of the guide-rods, a sprocket-chain 25 engaging the teeth on said adjusting-nuts, and toggle-levers connected to the crank-arms and pivoted to the base and movable platform, respectively, for reciprocating the latter, substantially as specified.

In testimony that I claim the foregoing as my own I hereunto subscribe my name in the presence of two witnesses.

GILBERT H. DENTON.
